UNITED STATES PATENT OFFICE

1,955,509

DISPLAY STAND

Clarence S. Moeckel, Atlanta, Ga., assignor to
 Southern Spring Bed Company, Atlanta, Ga.,
 a corporation of Georgia

Application April 21, 1933, Serial No. 667,296

1 Claim. (Cl. 211—85)

The principal object of this invention is to provide an improved stand for displaying packages of merchandise that is of a simplified structure and can be collapsed into a small space for shipment or storage.

Other objects and features of novelty will be apparent from the description taken in connection with the drawing in which,

Figure 1 is a perspective view of one embodiment of the invention;

Figure 2 is a side elevation with parts broken away, showing the stand in collapsed position;

Figure 3 is a sectional elevation showing a detail; and

Figure 4 is a perspective view of another form of the invention.

Referring to the drawing, the stand comprises a frame consisting of the substantially upright side members 10 and 11 connected by the transverse top member 12. Preferably this frame is made from a single piece of angle iron bent into the shape shown. The members 10 and 11 are reversely disposed so far as the angles of the angle irons are concerned, that is to say, the rearwardly projecting legs of the angles are on the outer sides of the frame and the front legs are in the same plane and project toward each other.

This frame is divided into substantially rectangular frame openings by cross bars or rests 13, these bars being secured to the side bars 10 and 11 as by riveting. Located above each of the cross bars 13 are U-shaped members 14 having their free ends 15 pivoted at 16 to the inner sides of the rearwardly extending legs of the side members 10 and 11. The free ends 17 of these U-members abut the inner surface of the front legs of the angle irons so that the members 14 are thus prevented from swinging downwardly. The upper corners 18 are rounded to permit these members to swing upwardly into the plane of the frame.

For the purpose of holding the frame in a position slightly inclined with respect to the vertical, an easel support is provided. As shown, this consists of a U-shaped bar having side members 19 and 20 and a connecting bottom member 21. The free ends of the side members 19 and 20 are pivoted at 22 to the outer sides of the main frame. If desired, the corners of the U-shaped member may be reinforced by the braces 23 and 24. To hold the easel support in proper position relative to the frame, the bars 25 are provided which are pivoted at 26 to the outer sides of the members 19 and 20. These bars are formed

with hooked ends 27 which are adapted to hook over bolts 28 projecting inwardly from the side legs of the members 10 and 11. If desired, the frame may be provided with the bolt holes 31 for securing advertising cards to the top of the frame.

The packages to be displayed are stood upon the cross bars 13 and held against falling out backwardly by the U-members 14. A series of packages on the top bar 13 is shown in dotted lines, and it will be noted that a single pivoted U-member 14 retains several packages.

In order to collapse the stand for shipment or storage, the U-members 14 are swung upwardly into the plane of the frame. Then the bars 25 are unhooked and allowed to swing downwardly to a vertical position. Thereafter the easel support is swung substantially into the plane of the frame. It will be noted that the collapsed frame has substantially no greater thickness than the thickness of the side members 10 and 11.

Figure 4 illustrates what may be termed a double stand. It comprises the side members 10^a and 11^a which are like the ones already described in connection with Figure 1 but have in addition short horizontal extensions 29 and 30, respectively, at their upper ends. The second display stand has side members 10^b and 11^b like the members 10 and 11, and these are pivoted at their upper ends to the free ends of the horizontal extensions 29 and 30.

Both frames are provided with cross bars 13 and pivoted U-shaped retaining members 14, the same as in the form of the invention shown in Figure 1.

To hold the two frames in inclined positions, the bars 25^a are provided, which are pivoted at 26^a to the side members of one frame and have hooked ends taking over the bolts 28^a on the other frame. When these bars are unhooked and the U-shaped retaining members 14 swung upwardly into the planes of their respective frames, the two frames can be swung toward each other and thus occupy a relatively small space for storage or for shipment.

The extensions 29 and 30 may be provided with short uprights 32 to support a card carrying advertising or other display matter.

Having thus described the invention, what is claimed as new and desired to be secured by Letters Patent is:

A display stand comprising, in combination, a frame including two parallel and substantially upright side members made of angle iron and reversely disposed with the front flanges of said irons in the same plane, spaced horizontal cross

bars connecting said side members and dividing the frame into a plurality of rectangular frame openings, a U-shaped normally rearwardly directed and substantially horizontally disposed retaining member for each opening pivoted to the side members for limited swinging movement into the plane of the frame or to a position substantially at right angles thereto, the U-shaped members being pivoted to the rearwardly directed side flanges of the angle iron frame members with their tip ends abutting the front flanges, the up-

per corners of said tip ends being rounded to permit the U-shaped members to be swung upwardly into the plane of the frame, each U-shaped member forming, with said side members and one of said cross bars, a pocket to receive a plurality of packages to be displayed with the packages resting on said cross bar, and means adapted to be collapsed substantially into the plane of the frame to hold the frame inclined slightly from the vertical.

CLARENCE S. MOECKEL.
